CLAIM

The ornamental design for a keyboard with stand, as shown and described.

DESCRIPTION

FIG. 1 is a front, right, top perspective view of the claimed design;

FIG. 2 is a rear, right, top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof; and,

FIG. 8 is a right-side elevational view thereof.

The broken lines shown in the drawings represent portions of the keyboard with stand and form no part of the claimed design.
